UNITED STATES PATENT OFFICE.

ROBERT J. HARPER, SR., OF CHICAGO, ILLINOIS.

ELEVATOR-DOOR LOCK.

Application filed February 14, 1922. Serial No. 536,422.

To all whom it may concern:

Be it known that I, ROBERT J. HARPER, Sr., a citizen of the United States, residing at Chicago, in the county of Cook and State of Illinois, have invented certain new and useful Improvements in Elevator-Door Locks; and I do hereby declare the following to be a full, clear, and exact description of the invention, such as will enable others skilled in the art to which it appertains to make and use the same.

The invention relates to elevators and more particularly to safety means whereby to secure the door at a landing and thereby prevent a casualty such as frequently occurs when doors at the various landings of an elevator shaft are not made secure.

The present invention relates to lock means for securing the door at each of the floors or landings of an elevator shaft and aims to provide a lock mechanism which may be easily and quickly applied and which is simple in construction, efficient and not liable to derangement and which, moreover, embodies a few number of parts.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a fragmentary elevation of a freight elevator provided with lock means embodying the invention.

Figure 2 is an edge view of the parts illustrated in Figure 1, partly in section.

Figure 3 is a section on the line 3-3 of Figure 1, looking in the direction of the arrows and showing a key in position for opening the lock from the floor side.

Figure 4 is a horizontal section on the line 4-4 of Figure 1,

Figure 5 is a horizontal section on the line 5-5 of Figure 2,

Figure 6 is a horizontal section on the line 6-6 of Figure 2, and

Figure 7 is a detail perspective view of the lock frame which is attached to the elevator door.

Corresponding and like parts are referred to in the following description and designated in the several views of the drawings by like reference characters.

The numeral 1 designates a side wall of the structure enclosing the elevator shaft or well at a landing or floor. A door 2 is provided for closing the opening leading to the well or shaft and in the present instance said door is mounted to slide vertically although the direction of movement is immaterial with reference to the operation of the lock mechanism. A flange 3 or like part projects inwardly from the side wall 1 bordering upon the door opening and cooperates with a companion flange 4 at the adjacent edge of the door 2, the two flanges 3 and 4 abutting when the door is closed. These parts may be of any construction and arrangement, depending upon the style and make of elevator.

The lock comprises a rectangular frame 5 which is bolted or otherwise secured to the inner side of the door 2 adjacent the edge provided with the flange 4. In the present instance, the frame 5 is recessed to receive nuts 6 which are countersunk and cooperate with bolts 7, whereby the frame 5 is firmly attached to the door 2. A catch 8 is pivoted to the frame 5 and, as shown, consists of a plate having a flange 9 at one end and along opposite sides to embrace one end and opposite sides of the frame 5. The engaging end of the plate is formed with a shoulder 10 which is adapted to engage under the flange 3 and secure the door 2. The shouldered end 10 of the plate forming the catch 8 is extended and deflected laterally so as to ride upon the flange 3 as the door 2 closes. Lugs 11 project inwardly from the catch 8 and are apertured to receive a pintle 12 which passes through opposite members of the frame 5. The lugs 11 are disposed to engage the inner side of the members of the frame 5 thereby preventing lateral displacement of the catch. Washers 13 are secured to opposite ends of the pintle 12 to prevent displacement thereof and yet admit of removal of the pintle and catch as occasion may require. Springs 14 are interposed between the catch 8 and frame 5 to normally hold the shouldered end 10 of the catch in position to engage the flange 3,

whereby to lock the door when in closed position. The springs 14 are of expandible helical form and are retained in place by

recesses 15 formed in the frame 5 and tits 16 provided on the catch 8 engaging opposite ends of the springs.

The invention is particularly adapted for the doors of freight elevators and the lock mechanism may be applied to vertically or horizontally sliding doors as will be readily appreciated. The catch 8 may be operated from the floor side of a landing by means of a key 17 which is adapted to be thrust through an opening 18 formed in the frame 5 and catch 8 in coincident position, said key embodying a turnbuckle 19 which, after clearing the inner side of the catch 8, assumes a position crosswise of the opening 18, whereby a pull upon the key 17 operates the catch 8 to effect release thereof from the flange 3 whereby the door 2 may be opened.

Certain liability bureaus require the locks on all elevator doors to be blank but one so that access to the car may be had at one landing only. To meet these conditions, it is proposed to have all the locks applied to the doors of an elevator shaft blank with the exception of one which will be constructed so as to cooperate with a key as indicated most clearly in Figure 3 of the accompanying drawings. This result may be accomplished by not boring the elevator doors to which the locks are attached with the exception of the one designed to be opened by means of the key 17.

What is claimed is:

1. An elevator door lock comprising an

open frame, a catch comprising a plate having an engaging shoulder at one end and provided at its opposite end and along its sides with an off-standing flange, said flange to be disposed along the outer wall of said open frame, perforated lugs carried by said catch and extending into said open frame and engaging the inner side walls thereof, a pintle passing through said frame and said perforated lugs to pivot said catch to said frame, and spring means disposed between said frame and catch to normally hold said catch in fastening position.

2. A lock for an elevator door comprising a frame, a spring actuated catch pivoted to the frame, both the frame and catch having openings in coincident position, and a key for operating the catch and embodying a turnbuckle, said key being adapted to be removably thrust through the openings of the frame and catch, the turnbuckle assuming a position crosswise of the openings after clearing the catch, said turnbuckle serving to prevent withdrawal of the key from the side of the lock from which it is inserted and serving further when the key is pulled toward said side to engage the catch and move the same to door releasing position.

In testimony whereof I affix my signature in presence of two witnesses.

ROBERT J. HARPER, SR.
